(57) **CLAIM**

The ornamental design for a coin holder, as shown and described.

DESCRIPTION

FIG. 1 is a front elevational view of a first embodiment of a coin holder, showing my new design, in a closed position; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; FIG. 7 is a cross-sectional view taken along line 7-7 of FIG. 5; FIG. 8 is a perspective view thereof; FIG. 9 is a front elevational view of a second embodiment of a coin holder, showing my new design, in an open position; FIG. 10 is a rear elevational view thereof; FIG. 11 is a left side elevational view thereof; FIG. 12 is a right side elevational view thereof; FIG. 13 is a top plan view thereof; FIG. 14 is a bottom plan view thereof; FIG. 15 is a cross-sectional view taken along line 15-15 of FIG. 13; and, FIG. 16 is a perspective view thereof. The portions of the coin holder shown in broken lines form no part of the claimed design.
